UNITED STATES PATENT OFFICE.

CHARLES E. ONGLEY, OF NEW YORK, N. Y., ASSIGNOR TO GEORGE J. SCHOEFFEL, OF SAME PLACE.

VALVE-CONTROLLING DEVICE.

SPECIFICATION forming part of Letters Patent No. 570,045, dated October 27, 1896.

Application filed October 30, 1893. Serial No. 489,506. (No model.)

To all whom it may concern:

Be it known that I, CHARLES E. ONGLEY, a citizen of the United States, residing at New York city, in the county and State of New York, have invented a certain new and useful Improvement in Valve-Controlling Devices, of which the following is a specification.

My invention relates to apparatus in which the valves of a cylinder are operated or controlled electrically, and to the construction of valves especially adapted for that purpose, which valves may, however, be operated, if desired, otherwise than electrically.

In the drawings like letters refer to like parts.

Figure 1 is a sectional view of apparatus embodying my invention; and Fig. 2, an elevation of the electromagnets, showing also the auxiliary valves, one of which is shown in section.

A is a cylinder having a piston-rod a' and ports or valve connections a^2 and a^3 and a^4 and a^5 , a^2 and a^3 leading through a channel into one end of the cylinder and a^4 and a^5 into the other end thereof.

B is a valve-chest annexed to the cylinder A, having a supply-pipe at b' . The valve-stem b^2 oscillates in the valve-chest B and is provided with two heads b^3 and b^4 , which are arranged to open the ports leading to one end of the cylinder A to admit the pressure thereto, and at the same time to close the ports to the other end of the cylinder to exclude the same pressure, but opening the latter to permit a vent from that end of the cylinder. The spiral springs b^5 and b^6 lie between the heads of the valve-chest and the heads of the valve-stem and are of equal tension.

y and y' are vents through which the pressure is discharged.

C is a cylinder having a piston-rod c' , provided with a head at one end and secured at the other to the valve-stem b^2 , said cylinder being provided with the valves c^3 and c^4 and vents c^9 and c^{10} . The valve c^4 is shown in section in Fig. 2, and the valve c^3 is shown in elevation.

D' and D^2 are electromagnets suitably mounted and having armatures d^3 and d^4 , secured to the valve-stems c^5 and c^6 of the valves

c^3 and c^4 . Electrical circuit connections extend to the electromagnets D' and D^2 , and means are provided to control these parts. Any of the well-known connections and circuit-controllers may be employed for the purpose. Pressure is supplied to the valve-chest B through the supply-pipe b' , and thence, as related, to cylinder A, and pressure is supplied to the cylinder C through the valves c^3 and c^4 , through the supports, which are also pipes, c^7 and c^8 . The channel c^{11} conveys the pressure from valve c^3 to the end of the cylinder C.

E is a lever to operate the valve by hand.

The operation of my device is as follows: The position of the device shown in Fig. 1 is that when the machinery is at rest, the pressure being equalized. When I desire to operate the same electrically, I close the circuit to one of the magnets D' or D^2 , thus energizing that magnet and attracting its armature thereto, thereby operating one of the valves c^3 or c^4 to admit pressure into one end of the cylinder C. This pressure operates to move the piston-rod c' and valve-stem b^2 and the heads b^3 and b^4 , the movement being, for instance, in the direction of the arrow 1. The ports a^2 and a^3 are thereby opened to the pressure and the ports a^4 and a^5 are closed to it, the ports a^4 and a^5 being, however, opened to the vent y' . Thus pressure is admitted into the cylinder A to move the piston-rod a' in the direction indicated by arrow 2. Making the circuit through the other of said electromagnets operates in the same way to move the other valve of the cylinder C and to move the heads b^3 and b^4 in the reverse direction of that last described, thus opening and closing the ports of the cylinder A to move its piston-rod in the reverse direction.

The spiral springs b^5 and b^6 are of equal tension and operate to hold the piston-heads b^3 and b^4 in the normal positions shown in Fig. 1, thus equalizing the pressure in the cylinder and holding the piston-rod stationary.

In operating my device any liquid or fluid under pressure may be employed, such as steam, water, and air.

The advantage of using steam or its equivalent in the cylinder C is, first, that it is very

rapid in its operation, and, second, that when the steam or air is cut off the same condenses or escapes through the ports c^9 or c^{10} , leaving the apparatus free to be operated by hand 5 with the lever E.

This device is particularly useful for the reason that it may be applied to the valve of any engine without interfering with or altering the existing machinery, and leaving the 10 same capable of being controlled either electrically or by hand at will.

What I claim is—

In a valve-controlling device, the valve consisting of a valve-chest having inlet and 15 outlet ports and a valve-stem having two

heads to control said ports and two springs bearing with equal tension upon the valve-stem heads, in combination with a motor to operate said valves, consisting of a cylinder having operative valves and piston-rod and electromagnets in circuit having armature secured to the valve-stems of said motor and means to control the circuit. 20

This specification signed and witnessed this 25th day of October, 1893.

CHARLES E. ONGLEY.
